ROTARY JAR

John H. Bishop, Los Angeles, Calif., assignor of
sixteen and two-thirds per cent to Jack Dono-
van, Whittier, Calif.

Substitute for abandoned application Serial No.
382,178, July 30, 1929. This application Feb-
ruary 11, 1936, Serial No. 63,372

2 Claims. (Cl. 255—27)

This is a renewed application filed in place of
my forfeited application, Ser. No. 382,178, filed
July 30, 1929.

This invention relates to a rotary jar, by means
5 of which a tool which has become fastened in
the hole may be jarred loose by the usual rotat-
ing movement of the drill pipe.

An object of my invention is to provide a rotary
jar which can be used during the drilling of the
10 well, and which can be brought into operation
to jar the tool by pulling upwardly on the drill
pipe, and then rotating the drill pipe in the usual
clockwise direction.

A further object is to provide a rotary jar of
15 the character stated which will in no way inter-
fere with the usual rotary drilling of a well.

Other objects, advantages and features of in-
vention may appear from the accompanying
20 drawing, the subjoined detailed description, and
the appended claims.

In the drawing:

Figure 1 is a longitudinal sectional view of my
jar.

Figure 2 is a sectional view taken on line 2—2
25 of Figure 1.

Figure 3 is a fragmentary side elevation of the
jarring stem, the head thereon being shown in
section.

Figure 4 is a fragmentary longitudinal sectional
30 view of the lower part of the body.

Referring more particularly to the drawing,
the numeral 1 indicates the cylindrical body
of the tool which is provided with threads upon
the upper end thereof as at 2, whereby the tool
35 is secured to the drill pipe or the like. A jarring
stem 3 is adapted to extend into the cylindrical
and tubular body 1 and the stem is provided with
a box or pin 4 on the lower end thereof to which
the tool, such as a bit is secured. A heavy multi-
40 sided nut 5 is formed immediately above the box
4 and is preferably integral with the stem and box.

The body 1 is formed with a multi-sided recess
6 in the bottom thereof which fits over the nut 5
for the purpose of rotating the tool as will be
45 further described. The stem 3 is provided with
a head 7 on the top thereof, said head being
preferably screwed onto the top of the stem as
shown in Fig. 3. The head 7 is locked in position
on the stem in any suitable manner, for example,
50 by means of a nut 8 which is hexagonal on the
outside, and which fits over the square 9 on the
top of the stem. The hexagonal part of the nut
fits into an appropriate recess in the head and a
cotter key 10 extends thru the stem 3 above
55 the nut.

The head 7 is provided with a slightly enlarged
ring 11 on the top thereof, and the body 1 is
provided with a shoulder 12 which is adapted to
engage the ring 11 when the tool is removed from
60 the well. The head 7 is formed with a plurality

of cam surfaces 13 on the bottom thereof, said
surfaces being adapted to cooperate with cam
surfaces 14 on the top of a slidable sleeve 14 on
the stem 3. The sleeve 15 is caused to rotate
with the body 1 by means of a plurality of pins 16
which extend into key ways 17 in the sleeve.

A coil spring 18 surrounds the stem 3 and bears
against the bottom of the sleeve 15 and against
a ring 19 which rests upon shoulders 20 in the
body 1. During the drilling operations of the
well, when the bit is progressing into the forma-
tion, there is considerable weight upon the bit
from the drill pipe above, and this weight holds
the body 1 in position around the nut 5 as shown
in Figure 1. The spring 18 is not long enough to
hold the sleeve 15 against the head 7 during the
normal drilling operation. If the bit becomes
stuck in the hole, the drill pipe is pulled up-
wardly in order to release the body 1 from the
nut 5 and this action also compresses the spring
18, which in turn, forces the sleeve 15 against
the head 7. Continued rotation of the drill pipe
in a clockwise direction will drive the sleeve, and
the head 7 will be stationary because the stem 3
is secured to the bit. The relative rotation of
the members 7—15 will cause the cam surfaces
13—14 to slide over each other and thus create
a bump or jar upwardly against the stem 3. This
continued bumping or jarring will eventually re-
lease the bit so that the drilling operations can
be continued. In continuing to drill, it is only
necessary to again permit the weight of the drill
pipe to be exerted upon the bit and the recess 6
of the body 1 will fit over the nut 5, and the bit
will be rotated in the usual manner.

Having described my invention, I claim:

1. A rotary jar comprising a body adapted to
be secured to drill pipe or the like, a stem adapted
to extend into the body, tool coupling means on
the stem, a multi-sided driving nut on the stem,
said body having a recess adapted to fit over the
nut, a head on the stem, a sleeve rotatably
mounted on the stem, driving pins extending
from the body into the sleeve, said head and
sleeve being provided with co-acting cam sur-
faces, and spring means yieldably urging said
cam surfaces together.

2. A rotary jar comprising a body adapted to
be secured to drill pipe or the like, a stem adapted
to extend into the body, tool coupling means on
the stem, a multi-sided driving nut on the stem,
said body having a recess adapted to fit over the
nut, a head on the stem, a sleeve rotatably
mounted on the stem, driving pins extending from
the body into the sleeve, said head and sleeve
being provided with co-acting cam surfaces, and
a coil spring surrounding the stem and adapted to
bear against the sleeve to yieldably urge the same
against the head.

JOHN H. BISHOP. 60
